UNITED STATES PATENT OFFICE.

SAMUEL S. GOSSARD, OF CHICAGO, ILLINOIS.

LACING-EYE.

SPECIFICATION forming part of Letters Patent No. 781,336, dated January 31, 1905.

Application filed March 2, 1904. Serial No. 196,198.

To all whom it may concern:

Be it known that I, SAMUEL S. GOSSARD, a citizen of the United States of America, and a resident of Chicago, in the county of Cook and State of Illinois, have invented certain new and useful Improvements in Lacing-Eyes, of which the following is a specification.

The main object of my invention is to provide an improved form of lacing-eye of simple and durable construction which will permit the lace to be freely drawn through same with but slight friction and wear on the lace. I accomplish this object by the device shown in the accompanying drawings, in which—

Figure 1 is a plan of part of a corset-lacing embodying my invention. Fig. 2 is an enlarged plan of one of the lacing-eyes. Fig. 3 is a section of the device shown in Fig. 2, taken on the line 3 3. Fig. 4 is an underneath view of one of the lacing-eyes.

In the device shown the body of the eye is stamped out of sheet metal to form the spheroidal ball-retaining part 1 and the shanks 2, which are separated to form the eye at 3 and lie flat against each other at 4, where same are connected to the stay 5 by means of the rivet 6. The spheroidal part 1 is formed around the ball 7 and is stamped of suitable size to permit said ball to freely revolve within the part 1. The lace 8 passes through the eye at 3 and bears mainly against the ball 7, which revolves when the lace is drawn along through the eye, as would be the case in tightening up or loosening the lacing shown in Fig. 1 or in shifting same through the eyes, as is done through changes in the position of the wearer. The shanks of the eye are bent together in the form shown before attachment to the stays 5 or the other article to which it may be desired to attach said eyes. The eyes may therefore be completed before attachment with the parts, bent into suitable form to properly retain the balls and permit free rotation of same.

It will be understood that said eyes may be used in connection with other forms of lacings as well as the corset-lacing shown. The eyes are preferably attached alternately, as shown in Fig. 1, so as to give a free lead to the lace.

What I claim as my invention, and desire to secure by Letters Patent, is—

1. A lacing-eye comprising a ball, a piece of sheet metal bent upon itself and having its bent part expanded to form a spheroidal shell loosely fitting around and adapted to retain said ball, said shell being partly open at one side to permit the lace to bear on the ball, and one of the ends of said piece being extended to form a shank, substantially as described.

2. A lacing-eye comprising a ball, a piece of sheet metal bent upon itself and having its bent part expanded to form a spheroidal shell loosely fitting around and adapted to retain said ball, said shell being partly open at one side to permit the lace to bear on the ball, and the ends of said piece being brought together to form an eye at the open part of the shell and being extended to form a shank, substantially as described.

3. A lacing-eye comprising a ball, a piece of sheet metal bent upon itself and having its bent part expanded to form a spheroidal shell loosely fitting around the ball and being partly open at one side, one end of said piece being extended to form a shank at the open side of the shell, and the expanded part curved laterally around the ball and serving as a web for bracing the bend in said piece and retaining the ball, substantially as described.

Signed at Chicago this 27th day of February, 1904.

SAMUEL S. GOSSARD.
